UNITED STATES PATENT OFFICE.

WILLIAM MOSMAN LUEBBERT, OF SAN FRANCISCO, CALIFORNIA.

HANGAR.

1,313,547.

Specification of Letters Patent. Patented Aug. 19, 1919.

Application filed March 16, 1918. Serial No. 222,892.

To all whom it may concern:

Be it known that I, WILLIAM M. LUEBBERT, a citizen of the United States, residing at San Francisco, in the county of San Francisco and State of California, have invented a new and useful Hangar, of which the following is a specification.

This invention relates to hangars and similar structures one of its objects being to 10 provide an inclosure made of canvas or other suitable fabric and which can be transported conveniently from place to place and set up for use readily.

A further object is to provide a structure 15 of this character which is entirely free of supporting poles or the like inside the structure but which affords a clear, unobstructed space coextensive with the area of the hangar.

20 Another object is to provide novel means for supporting the roof of the structure and which provides means whereby an aeroplane, an aeroplane motor, or other objects can be suspended from the roof of the hangar.

25 With the foregoing and other objects in view which will appear as the description proceeds, the invention consists of certain novel details of construction and combinations of parts which will be hereinafter more fully described and pointed out in the claim, it being understood that various changes may be made in the construction and arrangement of the parts without departing from 30 the spirit of the invention as set forth in the appended claim.

In the accompanying drawings the preferred form of the invention has been shown.

In said drawings—

40 Figure 1 is a side elevation of a hangar or other structure embodying the present improvements.

Fig. 2 is a vertical transverse section.

Fig. 3 is a plan view.

45 Fig. 4 is an elevation of one end of the structure.

Fig. 5 is a plan view of a modified form of hangar.

Fig. 6 is a vertical transverse section there- 50 through on line 6—6.

Fig. 7 is a detail perspective view of a portion of one of the reinforcing cables and the fabric secured thereto.

Fig. 8 is an enlarged section on line 55 8—8, Fig. 2.

Fig. 9 is a detail view of a portion of one of the bridles and its supporting ring.

Referring to the figures by characters of reference, 1 designates masts set up in parallel rows and provided with guys 2 the lower ends of which are suitably anchored. The guys extend outwardly from the masts, as shown in the drawings thus to prevent the masts from bending or falling toward the masts of the opposed series. The upper 65 ends of the masts are properly tied together by cross cables 3 and by side cables 4.

The canvas or other fabric inclosure is erected between the masts and is provided with side walls 5 and a roof 6, said roof being provided with a central ridge 7. The roof fabric is secured along the edges of the roof, along the ridge, and wherever reinforcement is desired, to reinforcing means preferably consisting of a metal cable 8 70 having a covering 9 of burlap or the like which, in turn, is wrapped with ordinary rope, as at 10. The roof fabric is sewed to the burlap and rope wrapping and will not be quickly worn out along its points of attachment because it is protected from the metal cables by the fabric wrappings. The reinforcing cables properly wrapped have been indicated generally at 8 in Figs. 2 and 3. 85

The ridge of the inclosure is supported by short hangers 11 which are suspended from the centers of the cross cables 3 and are suitably secured to the reinforcing cable 8 extending along the ridge. Where the end portions of the roof are inclined downwardly from the ends of the ridge, as shown at 12, these hanger connections are not employed. Instead, and as shown in Fig. 4, supporting cables 13 are secured to the centers of the transversely extending reinforcing cables on said portions 12 and diverge upwardly where they are secured to the upper ends of the adjacent masts. This arrangement is shown clearly in Fig. 4. 90 95 100

Reinforcing cables are extended transversely of the roof 6 from the points of connection between the hangers 11 and the ridge cable 8, to the sides of the roof 6 and secured to each of these cables at points equidistant from the hanger and the sides of the inclosure are the ends of bridles 14 the intermediate portions of which work within rings 15 or the like secured to the lower ends of hangers 16 extending inwardly and down- 105 110

wardly from the masts 1. The points at which the bridles have been connected to the cables 8 have been indicated at 17, 18, 17' and 18' in Fig. 2. A bridle 19 is secured at 5 its ends to the cable 8 at the points 18 and 18' and the intermediate portion of the bridle is arranged to work within a ring 20 or the like connected to the central portion of a lower cross cable 21. Cable 21 is secured at 10 its ends to opposed masts. Additional rings or the like, indicated at 22, are secured to the cable 21 between the masts 1 and the ring 20 and working within one of these rings 22 is a bridle 23 one end of which 15 is fastened at the point 17 while its other end is fastened at the point 18'. Another bridle 24 is extended through the other ring 22 and is fastened at the points 18 and 17'. Thus it will be seen that three suspension 20 points are provided along each cross cable 21, namely, at 22, 20 and 22, there being bridles extending from these points for distributing a load to the bridles 14 which, in 25 turn, distribute the load to the hangers 16 and thence to the masts.

By providing a truss such as described the roof of the structure can not only be held up by exterior supports, thus leaving an extensive unobstructed area within the 30 inclosure, but it is also possible to support heavy loads, such as aeroplanes and aeroplane motors, off of the ground within the inclosure. Suitable hangers, indicated generally at 25, may be provided for this purpose.

Braces, such as the crossed braces 26 shown in Fig. 1, may be provided wherever deemed essential. The end cross cables 8 used for reinforcing the roof can be provided, in addition to the braces or hangers 3, with bridles 27 the intermediate portions of which work within rings 28 at the ends of hangers 29 extending downwardly from the adjacent masts. Curtains 30 can be supported upon the end cables 8 and, by opening laterally these curtains will afford ample room for the movement of an aeroplane into and from the inclosure.

The structure heretofore described can be 50 used as a large hangar or for various other purposes where a large portable inclosure is desired. In Figs. 5 and 6, however, has been shown a small portable hangar for emergency use and which is designed to hold 55 a single machine only. By referring to Fig. 5 it will be noted that, in plan the hangar

follows the general configuration of an aeroplane, it being provided with a broad front end portion 31 while the sides of the remaining portion converge rearwardly. The 60 fabric constituting the roof of the structure is reinforced in the manner hereinbefore described and the ends of the cross reinforcing cables 32 are attached to masts 33. Rings 34 or the like may be attached to the 65 cables 32 at intermediate points and working within these rings are bridles 35. One end of each bridle is secured to a mast at one side of the hangar while the other end of the bridle is secured to a mast at the 70 other side. In order to provide a central point of suspension within the hangar a cable is attached to the roof at the points 34 and has a ring or the like 36 mounted on or secured to the intermediate portion of the 75 cable, said cable being designated at 37. Hangers 38 can be suspended from the points 34 to provide additional points of suspension.

What is claimed is:—

The combination with spaced masts and upper cross cables connecting the masts, of a fabric housing arranged between the masts and supported at the center of its roof by the cross cables, transverse reinforcing cables 85 secured to the roof portion of the housing, hangers converging downwardly from opposed masts and above the roof, a bridle slidably engaging and extending downwardly from each of the hangers, the ends 90 of each bridle being secured to one of the reinforcing cables at different distances from the side of the roof, bridles within the housing and each secured at its ends to the transverse reinforcing cables of the roof at 95 opposite sides respectively of the center of the roof and at the points of connection between the roof and the upper bridle, a lower cross cable connecting opposed masts and below the roof of the housing, spaced rings 100 secured to said cable and slidably engaged by the respective bridles below the roof of the housing, and hangers depending from said rings for supporting loads.

In testimony that I claim the foregoing as 105 my own, I have hereto affixed my signature in the presence of two witnesses.

WILLIAM MOSMAN LUEBBEET.
